CLAIM

The ornamental design for a 3-conductor strain relief, as shown and described.

DESCRIPTION

FIG. 1 is a perspective view of the 3-conductor strain relief, showing our new design;

FIG. 2 is a front elevational view thereof;

FIG. 3 is a rear elevational view thereof;

FIG. 4 is a top plan view thereof;

FIG. 5 is a bottom view thereof;

FIG. 6 is a left side view thereof; and,

FIG. 7 is a right side view thereof.

The broken-line disclosure in the views is for illustrative purposes only and forms no part of the claimed design.
